US0D1101934S

(12) **United States Design Patent** (10) **Patent No.:** **US D1,101,934 S**
(45) **Date of Patent:** **** Nov. 11, 2025**

(54) **ORAL IRRIGATOR**

(71) Applicant: **Shenzhen Yuxinyuan Electronic Technology Co., Ltd.**, Shenzhen (CN)

(72) Inventor: **Lei Yu**, Shenzhen (CN)

(73) Assignee: **Shenzhen Yuxinyuan Electronic Technology Co., Ltd.**, Shenzhen (CN)

(**) Term: **15 Years**

(21) Appl. No.: **29/941,674**

(22) Filed: **May 10, 2024**

(51) LOC (15) Cl. **28-03**

(52) U.S. Cl.

USPC **D24/111**

(57) **CLAIM**

The ornamental design for an oral irrigator as shown and described.

DESCRIPTION

FIG. 1 is a front, right and top perspective view of an oral irrigator, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged view of detail 9 in FIG. 1.

The dashed broken lines depict portions of the oral irrigator that form no part of the claimed design.

The dot-dash broken lines in FIGS. 1 and 9 depict the boundaries of the enlargements that form no part of the claimed design.

1 Claim, 9 Drawing Sheets
